UNITED STATES PATENT OFFICE.

ELWIN STRICKLAND, OF LOS ANGELES, CALIFORNIA.

UNION CABLE AND DRILL-TOOL SOCKET.

SPECIFICATION forming part of Letters Patent No. 730,414, dated June 9, 1903.

Application filed September 25, 1902. Serial No. 124,792. (No model.)

To all whom it may concern:

Be it known that I, ELWIN STRICKLAND, a citizen of the United States, residing at Los Angeles, county of Los Angeles, State of California, have invented certain new and useful Improvements in Union Cable and Drill-Tool Sockets; and I hereby declare the following to be a full, clear, and exact description of the same, reference being had to the accompanying drawings, in which—

Figure 1 is a longitudinal central section of a combined or union cable and a drill-tool socket embodying my invention, the parts being in the position they occupy at the instant the cable is freed of its load. Fig. 2 is a detached view of the upper or adjustable ratchet-plug of the outer member of the socket. Fig. 3 is a view of the lower or ratchet end of the part shown in Fig. 2. Fig. 4 is a detached view of the lower or fixed ratchet-plug of the outer member of the socket. Fig. 5 is a view of the upper or ratchet end of the part shown in Fig. 4. Fig. 6 is a detached view of the included or escapement member of the socket, which also performs the function of the cable-socket. Figs. 7 and 8 are respectively top and bottom or opposite end views of the parts shown in Fig. 6, showing the ratchet-faces thereof; and Fig. 9 is a detached view of a short section of brass or similar tubing, which extends up from the cable-socket or escapement member and which serves to shield the cable from wear where it passes through the upper annular ratchet-plug of the outer member or tool-socket.

Like symbols refer to like parts wherever they occur.

My invention relates to that class of devices intended to be interposed between and form the union of a drill-cable and drill-tools for utilizing the rotary movement incident to the unlaying of the cable-strands when loaded and their relaying when relieved of the load for the purpose of changing the position of the drill with relation to the cable on successive strokes of the drill, whereby the perfectly round character of the hole being drilled is preserved and the drill-tool prevented from sticking or wedging.

The common practice in drilling Artesian and like wells is to so manipulate the drill-

cable as to cause the drill-tool to vary its position at successive strokes for the purpose above recited, and this has also been in a measure automatically effected by utilizing the unlaying and relaying of the rope through the medium of simple swivels or combined swivels and ratchets or clutches; but such devices as heretofore constructed and combined, so far as I am aware, have not been adapted to control the extent of rotation of the drill or render its movements uniform and exact.

To overcome such objections as are incident to the usual swivel-and-clutch combinations employed for such purposes and to effect a limited and regulated step-by-step rotation of the drill, so that the operation of said drill shall be uniform and exact, is the object of my present invention, and this I accomplish by the interposition of an escapement device or mechanism between the drill-cable and drill-tools, and such a combination of cable, drill-tool, and interposed escapement device embodies the main feature of my invention.

In carrying out my invention I preferably so combine a cable-socket and a drill-tool socket, the former being the included member and being provided at its opposite ends with ratchet-teeth and the latter being the including member and provided at its opposite heads with corresponding ratchet-teeth, the ratchet-teeth on both members being inclined in the same direction, and said members having a relative radial and longitudinal movement, that the cable-socket shall constitute the escapement and the drill-socket the pallet member of the escapement combination, and such a construction embodies a second feature of my invention.

There are other minor features of invention, all as will hereinafter more fully appear.

I will now proceed to describe my invention more fully, so that others skilled in the art to which it appertains may apply the same.

In the drawings, A indicates the outer or including member of the socket and which may be termed the "drill-tool" socket, and B the inner or included member of the socket and which constitutes the cable-socket as well as the escapement member of the com-

bination, the two parts when combined constituting a union socket for the cable and the drill-tools.

The outer member A, which is of tubular form, is provided at its upper end with a slight shoulder 1, which somewhat reduces the bore above the same, where it is threaded, as at 2, for the reception of a threaded annular plug C, and said member A is also threaded at its lower end, as at 3, to form a box for the reception of the pin of a sinker-bar jar or drill-stem, as the case may be.

C indicates an annular plug having on its lower end ratchet-teeth *c* and threaded above, as at 2^a, where it engages the threaded interior or bore of the outer member A, so that said plug may be adjusted in the bore of the member A to compensate for wear of the ratchet-teeth of the escapement devices. The upper end of ratchet-plug C is provided with wrench-seats 4 and a jam-nut 5 or equivalent means, whereby the ratchet-plug may be fixed after adjustment.

D indicates a second annular plug having ratchet-teeth *d* on its upper end, and said plug D is secured in the lower end of the bore of the member A just above the box 3 by a dowel-pin 6 or in other suitable manner. The distance between the upper ratchet-teeth *c* and the lower ratchet-teeth *d* of the member A is slightly greater than the length of the included or escapement member B, with the teeth of which said teeth *c* and *d* correspond and engage alternately, as will hereinafter appear.

a a indicate vents or passages for the escape of any liquid which might otherwise impede the movement of the member B.

B indicates the included or escapement member of the device, and in this instance, as it is also the cable-socket, its interior is tapered below to permit of securing the cable therein and is threaded above, as at 7, to receive the lower threaded end of a short tube E, of brass or other suitable metal, through which the cable passes. This cable-socket and escapement member has at its opposite ends ratchet-teeth *b b'*, which correspond with and alternately engage the fixed ratchet-teeth *c* and *d* above and below on the upper and lower ratchet-plugs C and D of the member A.

E indicates a short tube of brass or other suitable metal threaded at one end, as at 8, to engage the thread 7 in the upper end of the bore of the cable-socket and escapement member B. The inner diameter of the tube E is such as to permit the passage of the drill-cable, which it incloses and shields against wear incident to the reciprocation and rotation of the cable, and its outer diameter is such as to permit it to reciprocate and rotate freely in the axial opening of the upper annular ratchet-plug C, through which it passes.

The ratchet-teeth *b* and *b'* of the inner or escapement member B and those *c d* of the outer member A correspond in form, as hereinbefore pointed out, and are made up of in-

clined and vertical sides, the number of teeth and length of their inclined faces (or width of base of tooth) being determined by the extent of rotation of the tool desired at each successive stroke, (in the present instance the teeth are shown as four in number,) and the inclination of the teeth will depend on the laying of the cable-strands. The included member B when released from load may be rotated by the relaying of the cable, and the ratchet-teeth *c* and *d* are preferably slightly out of alinement in order to insure the skipping of a tooth or the escapement action of the parts.

The construction of the several parts of the escapement-socket being substantially of the character hereinbefore pointed out, they may be assembled to constitute the union cable and drill-tool socket by first inserting the annular ratchet-plug C into the bore of socket member A from below, screwing it into the desired position, and after proper adjustment clamping it in position by the jam-nut 5, next screwing the threaded end of tube E into the threaded upper end of the bore of the member B, and passing the parts E B into the bore of the member A from below until the upper end of tube E projects slightly from the annular plug C and the ratchet-teeth *b* engage the ratchet-teeth *c*, after which the lower or fixed annular ratchet-plug D may be inserted and secured by the dowel-pin 6.

Of course when the device is to be secured to the cable the end of the cable will be passed through the annular plug C of the member A, drawn out at the lower end of said member A, and passed through tube E into the socket and escapement member B, where it will be secured in the usual manner, after which the cable will be drawn back, so as to carry the tube E into the annular ratchet-plug C and the part B within the bore of member A, after which the fixed ratchet-plug D will be inserted and secured by the dowel-pin 6, as before specified.

The operation of the union cable and drill-tool socket or escapement-socket will be as follows: When the load is on the cable, the ratchet-teeth *b c* will be in engagement and the parts or members A B will be locked and rotate together by reason of the elongating or unlaving of the strands; but at the instant the weight is released from the cable the part B will first rewind in the member A, which will cause the teeth *b' d* to engage, (see Fig. 1,) at which time the cable, being relieved of its load, will remain in that position until it receives the weight of the tools and until the longitudinal upward movement of the part B is effected, so that the upper tooth *b* skips or escapes the first or adjacent tooth *c*, and as this lift of the cable takes place and the weight of the drill-tools or load is again assumed the drill-socket member A and attached drill-tool make a partial (quarter) rotation equal to the width of the ratchet-tooth at its base.

The foregoing operation of the devices is repeated with each lift and drop of the tools, the teeth *b b'* of the escapement member *B* coacting with the teeth *c d* or pallets of the member *A* to limit and regulate the relaying of the cable and the extent of rotation of the drill-tool.

Having thus described my invention, what I claim, and desire to secure by Letters Patent, is—

1. A combined cable and drill-tool socket provided with escapement devices actuated solely by the unlaying and relaying of the drill-cable, substantially as and for the purposes specified.
2. In a combined cable and drill-tool socket, the combination of an inner cable-socket member provided with ratchet-teeth, and an outer drill-tool-socket member provided with corresponding ratchet-teeth, the ratchet-teeth on both members being inclined in the same direction, and said sockets being relatively movable longitudinally, substantially as and for the purposes specified.
3. In a combined cable and drill-tool socket, the combination with an included cable-socket member having ratchet-teeth at its opposite ends, of an including drill-tool-socket member having ratchet-teeth disposed to engage the ratchet-teeth of the rope-socket, the ratchet-teeth on both members being inclined in the same direction, and said members having relative rotary and longitudinal movement, substantially as and for the purposes specified.
4. In a combined cable and drill-tool socket, the combination with an including member having oppositely-disposed ratchet-teeth on its interior, of an included member having ratchet-teeth at opposite ends, the ratchet-teeth on both members being inclined in the same direction, and said members having a relative rotary and longitudinal movement,

substantially as and for the purposes specified.

5. In a combined cable and drill-tool socket, the combination with an included cable-socket member having oppositely-disposed ratchet-teeth, of an including drill-tool-socket member having on its interior two sets of ratchet-teeth arranged to engage the oppositely-disposed ratchet-teeth of the included member, one of the sets of ratchet-teeth of the including member being adjustable, substantially as and for the purposes specified.

6. In a combined cable and drill-tool socket, the combination with an including member, of an annular fixed plug having ratchet-teeth on one end, an annular screw-plug having ratchet-teeth on its inner end, and an included member having ratchet-teeth upon both ends, the included and including members being relatively movable, substantially as and for the purposes specified.

7. In a combined cable and drill-tool socket, the combination with a tubular drill-tool socket having its bore threaded at one end, of a threaded annular ratchet-plug which is seated in the threaded end of the bore of said drill-tool socket, a jam-nut for said threaded annular ratchet-plug, a second ratchet-plug oppositely disposed to said first-named ratchet-plug, a cable-socket having ratchet-teeth at its opposite ends, said cable-socket interposed in the bore of the drill-tool socket between the said ratchet-plugs, and provided with a tubular extension which extends through the upper annular ratchet-plug, substantially as and for the purposes specified.

In testimony whereof I affix my signature, in presence of two witnesses, this 13th day of September, 1902.

ELWIN STRICKLAND.
